(57) **CLAIM**

The ornamental design for a shell of a pet chase toy, as shown and described.

DESCRIPTION

FIG. 1 is a front perspective view of the shell of a pet chase toy in accordance with the present invention;

FIG. 2 is a rear perspective view thereof;

FIG. 3 is a front view thereof;

FIG. 4 is a rear view thereof;

FIG. 5 is a right side view thereof (the left side view is a mirror image thereof); and,

FIG. 6 is a top view thereof.

The portions of the drawings shown in broken lines are for illustration only and depict features forming no part of the claimed design.
